UNITED STATES PATENT OFFICE.

BOHN CHAPIN HICKS, OF MINNEAPOLIS, MINNESOTA, ASSIGNOR, BY MESNE ASSIGNMENTS, TO THE HICKS STOCK CAR COMPANY, OF CHICAGO, ILLINOIS.

STOCK-CAR.

SPECIFICATION forming part of Letters Patent No. 430,951, dated June 24, 1890.

Application filed March 17, 1890. Serial No. 344,120½. (No model.)

To all whom it may concern:

Be it known that I, BOHN CHAPIN HICKS, a citizen of the United States, residing at Minneapolis, in the county of Hennepin and State of Minnesota, have invented certain new and useful Improvements in Double-Deck Stock-Cars, of which the following is a specification.

This invention relates to that class of stock-cars known as "double-deck stock-cars," wherein there is employed a horizontal partition or deck which divides the car into two floors or decks. The object of this deck is to double the carrying capacity of the car when used for the transportation of small animals, like sheep and swine. Since it is desirable to utilize the same car both for sheep and swine and for large animals—such as cattle and horses—it is customary to make the sections of which the deck is composed movable, so that they may be moved out of the way when cattle or horses are to be transported.

The present invention relates to this class of double-deck cars, and has for its principal object the employment of the deck-sections in the formation of hay or fodder storage compartments or bins when said deck-sections are not in use for the transportation of sheep or swine. Coarse and bulky food—such as hay—is not required for sheep or swine during transportation, so that provision for carrying such food is not necessary when the car is divided by the deck for transporting sheep or swine; but when cattle or horses are transported, it is necessary to provide food-storage compartments or bins in the car.

The present invention consists in forming such food-storage compartments by elevating and sustaining the deck-sections (when not needed for transportation) to a horizontal position beneath the roof of the car at a sufficient height from the floor of the car to enable the car to be used for cattle and horses and sufficiently far beneath the roof to provide a food-storage space or compartment between the elevated deck-sections and the roof. The car is provided with feed-racks along its sides which communicate with the

storage-compartment thus formed, and doors are provided in the roof of the car to enable access to be gained to the storage-compartment.

A secondary feature of the invention consists in means for enabling access to be gained within the body of the car between the usual centrally-located doorways and the ends of the car. This means consists in a hinged swinging panel or hatchway, constituting a portion of the upper side of the car-body, and which carries on its inner face one of the feed-racks.

The present improvements are illustrated in the accompanying drawings, wherein—

Figure 1 is a vertical cross-section of a stock-car embodying the present improvements. Fig. 2 is a longitudinal vertical section of a portion of one end of the car; and Fig. 3 is an external side view of one end of the car, showing the manner of arranging the side panels or hatchways.

A' is the floor-frame; A², the side posts or stanchions; B', the belter-rail; B², the roof-plates or stringers, and A³ the roof of a stock-car.

The roof-frame consists of two sets of carlings or rafters D'D², set a short distance apart and leaving horizontal spaces a between them, the upper set of carlings supporting the roof 80 and the lower set contributing to the support of the double-deck sections E when they are elevated, as shown in Fig. 1.

Between each pair of the vertical side posts A², near their upper portions, a series of parallel inclined slats b' are arranged to form feed-racks for the animals, the upper ends of each series of slats being connected and supported by a cross-bar b², projecting slightly within the body of the car, over which the feed is inserted into the racks from the inside and beneath the horizontal plates or stringers B².

Along the outer edges of the roof A³ doorways are formed which afford access to the interior of the car, and these doorways are opened and closed by swinging doors A⁴.

When the double-deck sections are elevated, as shown in Figs. 1 and 2, they form a horizontal partition across the interior of the car,

leaving large spaces or compartments between them and the roof of the car; and it is the object of the present invention to utilize these compartments for the storage of feed 5 for the animals, which is inserted thereinto through the doors A⁴. When the double-deck sections are elevated, their outer edges rest upon and are supported by the cross-bars b² of the feed-racks and their inner edges are 10 supported by hooks d at the center of the car or otherwise.

The upper unslatted portions of the feed-racks are located above the upper surface of the double decks E when the latter occupy 15 their elevated position, so that the feed-racks are in communication with the storage-compartments and may be filled from the store carried by the double decks by means of a hay-fork inserted through the doors in the 20 roof. The decks E always occupy their elevated position when cattle or horses occupy the car, and as these animals are the only ones that require the coarser feed—such as hay—the decks will always be in position to be utilized 25 as supports for the feed when they are so required.

At the proper desired positions on the sides of the car, between the usual doorway A⁵ and the end of the car, the car-body is provided with 30 a removable panel or hatchway G for gaining access to the car. This panel G is located between two adjacent side posts A² at the upper part of the car, and is hinged or pivoted near its upper edge, so as to swing outwardly, as 35 indicated in Fig. 1. This swinging panel carries on its inner face the slats b' and cross-bar b², constituting one of the feed-racks, so that it is in effect an outwardly-swinging feed-rack. These swinging feed-racks afford easy 40 access to the interior of the car at points between the main doorway-openings and the ends of the car, which is a very important advantage in stock-cars, since the animals are frequently thrown down or become in-

jured, and it is of very great importance to 45 be able to get into the car for their relief in their immediate vicinity.

Each swinging feed-rack is provided with end plates c, which prevent feed in the rack falling out when the feed-rack is swung outwardly.

I claim as my invention—

1. A stock-car having openings in its roof and provided with feed-racks along its sides, in combination with double-deck sections 55 which are elevated and supported beneath the roof-frame when not in use to form a double deck, whereby said double-deck sections form the bottoms of food-storage compartments communicating with said feed-racks, substantially as set forth.

2. In a stock-car, feed-racks along the sides of the car, having projections extending into the interior of the car, in combination with movable deck-sections which, when elevated, 65 are supported along their outer edges by said inwardly-extending projections of the feed-racks, and means for supporting the inner edges of said deck-sections, whereby said deck-sections are capable of supporting a stock of 70 fodder for the animals in the car, the spaces above said deck-sections communicating with said feed-racks, substantially as and for the purpose set forth.

3. In a stock-car, an outwardly-swinging 75 feed-rack on the side of the car near its upper portion between the usual doorway-opening and the end of the car, said rack constituting a movable panel in the side of the car for enabling access to be had to the interior of the 80 car, substantially as set forth.

In testimony whereof I have hereunto set my hand in the presence of two subscribing witnesses.

BOHN CHAPIN HICKS.
